ABSTRACT

A tubular assembly having spaced-apart receptacles with polished bores is disposable in a well bore cementing cementing in place with the receptacle bores disposed above and below a producing formation. Upper and lower seal assemblies which are slidably and sealingly receivable in the spaced-apart receptacle bores are carried by a "long" tubing string and close off the receptacle bores to form an enclosed volume and provide a fluid conduit for fluids below the lower seal assembly. The upper seal assembly has an opening therethrough to the enclosed volume and is connectable to a "short" string of tubing. The effective cross-sectional area across the lower seal assembly is made equal to the effective cross-sectional area across the upper seal assembly by adjustment of the area of the opening through the upper seal assembly. The balancing of the effective cross-sectional areas eliminates movement of the seal assemblies during treating operations and eliminates the need for equipment to anchor the seal assemblies during treating operations.

FIG. 1

FIG. 2

METHOD AND APPARATUS FOR DEEP GAS WELL COMPLETIONS

BACKGROUND OF THE INVENTION

This invention relates to methods and apparatus for use in oil and gas wells, and more particularly, for deep gas well completions where long strings of tubing, high pressure and temperatures, huge stimulation treatments and high production rates give rise to unusual problems.

Multiple completions for deep gas well production have prompted the development of novel systems and apparatus for more efficient and economical operations. One such system is illustrated in U.S. Pat. No. 3,640,341 where a dual completion system employs a tubular receptacle below a liner hanger. A permanent production packer is anchored in the tubular receptacle and a sealing assembly is slidingly and sealingly received in the upper packer bore. If it is desired to stimulate this well by acidizing or work over the well using packers, plugs, bits, perforating tools or the like, it is necessary to remove the sealing assembly. If the assembly is not removed and hydraulic pressure is introduced between the upper sealing assembly and the production packer, the hydraulic forces generated will move the upper sealing assembly in an upward direction unless it is latched or anchored in the production packer. Alternatively, it has been proposed to use hold-down means on the upper seal assembly which are hydraulically actuated to anchor a sealing assembly relative to the receptacle. Both of these systems are subject to malfunctions because of mechanical complexity, the equipment cost is increased, and the operation is more complex to perform.

SUMMARY OF THE PRESENT INVENTION

The present invention involves the location in a borehole of upper and lower packer bore receptacles, each having packer bores so that such packer bores straddle an earth strata for the production of hydrocarbons. The receptacles are cemented at their locations and the earth strata intermediate of the receptacles is placed into fluid communication with a bore of tubular pipe or casing connecting the receptacles. The packer bores of the receptacles are closed off with packing means associated with a string of tubing to form an enclosed volume between the packer bores of the upper and lower receptacles and the bore of the connecting pipe or casing. The enclosed volume has its ends defined by the cross-sectional areas of the packer bores in the upper and lower receptacles exclusive of the cross-sectional area of such string of tubing.

Well treating fluids under pressure are introduced through the upper packing means to said enclosed volume where the cross-sectional areas of the upper and lower receptacles are adjusted relative to one another to have substantially equal areas thereby balancing the upper and lower areas and equalizing the upward and downward forces on the string of tubing within the enclosed volume.

The apparatus includes a packer bore receptacle assembly which has upper and lower packer bore receptacles. Packer means including an upper packer sealing assembly and a lower packer sealing assembly are constructed and arranged for a sliding and sealing reception respectively in the packer bores of the upper and

lower receptacles. The sealing assemblies are coupled to one another and spaced-apart by a section of tubing so that when the upper packer sealing assembly and the lower packer sealing assembly are slidingly and sealingly received in the respective packer bores that upper and lower cross-sectional areas are defined. The coupling of various parts herein described can be by any conventional means. Means defining a flow conduit extends through the upper cross-sectional area and opens 10 to volume defined between the upper and lower cross-sectional areas. The flow conduit means is sized in cross-sectional area relative to the upper cross-sectional area whereby the effective areas of the upper and lower cross-sectional areas are substantially equal.

For a better understanding of the present invention, together with other and further objects and features thereof, reference is had to the following description taken in connection with the accompanying drawing, 15 20 the scope of the invention being pointed out in the appended claims.

BRIEF DESCRIPTION OF THE DRAWINGS

Referring to the drawings:

25 FIG. 1 is a view in vertical cross-section through earth formations and a well bore, and illustrative of well completion systems according to the present invention; and

30 FIG. 2 is a diagrammatical view illustrating a central concept of the present invention.

DESCRIPTION OF THE INVENTION

Referring now to FIG. 1, a well completion system is illustrated in vertical cross-section through a producing 35 well which traverses earth formations. The borehole 10, which is drilled through the earth formations, typically has sections 11, 12, and 13 of different diameter where the bore size decreases as the depth of the well increases. In the particular illustration of FIG. 1, two 40 horizontal zones A and B of earth formations are illustrated from which it is desired and intended to separately and independently produce hydrocarbons or gas. In the completing of this well, a first tubular assembly 14 which is called "casing" is disposed between the earth's surface and to a selected strata depth, and the annulus 15 between the casing and the borehole section 10 is cemented in a well-known manner. Dependent 45 from the casing 14 is a liner 16, which is simply a tubular assembly telescopically received by the casing 14 and which extends below the casing to a lower or deeper strata depth. The liner 16 is attached to the lower end of the casing by a suitable, well-known cone and slip locking arrangement 17. The cone and slip arrangement typically permits insertion of the liner through the casing to the desired location. Actuation of 50 the slip and cone arrangement anchors the liner to the casing. The annulus 18 between the liner 16 and the borehole section 12 is also suitably cemented. Finally, depending from the liner 16 is a packer bore receptacle 55 assembly 19 (sometimes called PBR assembly) which is a tubular assembly telescopically received by the liner 16 and which extends below the liner 16 to the bottom of the borehole section 13. The PBR assembly 19 has a suitable slip and cone hanger arrangement 20 for attachment and anchoring of the PBR assembly 19 to the lower end of the liner 16. The hanger arrangement 20 can be hydraulically or mechanically set in any

60 65

conventional manner. Likewise, the hanger arrangement 20 can be located above or below a bore 22 of the PBR assembly 19 or can be entirely eliminated if the assembly is set on the bottom of the hole.

Cement is also disposed in the annulus 21 between the borehole section 13 and the packer bore receptacle assembly 19. As illustrated, when the casing 14, liner 16, and packer bore receptacle assembly 19 are installed in the borehole, the annulus from the bottom of the hole to the top of the hole is filled with cement which effectively prevents migration of gas and fluids between formations and to the earth's surface. The process and techniques for installing the casing, the liner, the packer bore receptacle assembly, cementing in place, and cleaning out the cement are well-known in the art.

With the tubular members of the casing 14, liner 16 and PBR assembly 19 disposed in the borehole, a flow conduit for hydrocarbons is provided. To couple the interior of the flow conduit to the producing strata, a perforating device such as a shaped-charged gun (not shown) or the like, is lowered through the conduit and used to perforate the earth strata section A and the earth strata section B, either conjointly or separately so that the earth formations are opened up through perforations to the interior of the conduit. With two producing zones, it is conventional to convey the output from the zones independently to the earth's surface by means of separate strings of tubing. In the prior art, this was typically accomplished by use of permanent production packers which were permanently set or anchored in the casing or pipe string. In this type of arrangement, the tubing strings were coupled to the packer devices. Where remedial or work-over operations were required, it was necessary to drill out the packers and utilize special equipment for such operations.

Since wells periodically require remedial treatment during their life, the requirement of permanent packers or anchors which dictated drilling operations and use of specialized equipment for treatment is burdensome. In this invention, I have eliminated the need for packers and the need for "hold-downs" or anchors in connection with a treating operation. Pursuing the method of this invention, a packer bore receptacle assembly 19 has upper and lower packer bore receptacles respectively with bores 22 and 23 which are polished and have a uniform diameter along their lengths. The upper and lower packer bore receptacles are coupled to one another by a tubular casing or pipe 21A and spaced apart so that the bores 22 and 23 are arranged to straddle the earth formation strata B. The bores 22 and 23 may be suitably coated with "teflon" or any other suitable preparation to protect the surface of the bores. As discussed heretofore, a perforating means (not shown) places the earth strata B into fluid communication by means of perforations 24 with the bore 41 of the PBR assembly 19 intermediate of the packer bores 22 and 23 of the upper and lower receptacles. Below the lower receptacle is a casing or pipe 23A which has a bore 24A. A lower set of perforations 25 extending into strata B places the strata B into communication with the open bore 24A of the casing 23A which is below the lower packer bore 23.

To produce fluids from the lower zone to the earth's surface, there are upper and lower seal assemblies 26 and 27 which are connected to one another by a heavy

wall tubing 28. The lower seal assembly 27 includes a series of annular chevron rings of packing material 29 disposed between upper and lower back-up flanges 30 and 31. The outer diameter of the chevron rings 29 is somewhat greater than the internal diameter of the polished bore 23. The chevron rings 29 are sufficiently resilient to allow their compression when inserted into the bore 23 so that the compression of the chevron rings provides a resilient force and extremely tight fluid seal with respect to the internal diameter of the bore 23. The upper seal assembly 26 similarly includes annular chevron packing rings 32 disposed between upper and lower shoulders 33 and 34, and having an outer diameter somewhat greater than the inner diameter of the polished bore 22. In a similar manner, the rings 32 are sufficiently resilient so that they are compressed when inserted into the bore 22. The upper end of the upper seal assembly is coupled by a short section 35 of a heavy walled tubing string to a production tubing string which extends to the earth's surface. With both sealing assemblies in the respective bores, fluids from the lower formation can be passed to the earth's surface via the conduit of the tubing.

The lower packer bore 23 of the PBR assembly 19 includes an upwardly facing flange portion 37. The spacing between a downwardly facing bottom shoulder 31 of the lower seal assembly 27 and downwardly facing bottom shoulder 34 of the upper seal assembly 26 is made such that when the bottom shoulder 31 engages the flange 37, the upper shoulder 34 will preferably be spaced slightly above an upwardly facing flange 38 so that downward weight applied to the tubing string 36 is applied to the lower flange 37. The length of the packer bore 22 between its uppermost shoulder and the lower flange 38 can be from 10 to 20 feet with 10 to 12 feet being a popular length. From the description thus far, it will be seen that the "long" string which includes the tubing sections 36, 35 and 28, and the upper and lower seal assemblies 26 and 27 can be inserted through the well casing and lowered until the lower seal assembly 27 lands on the flange 37, at which time the lower shoulder of upper seal assembly 26 is just short of engaging the upper flange shoulder 38. The movement of the tubing string and location of the packer seal assemblies in the packer bores requires only vertical movement. At the same time, the seal assemblies allow the use of maximum size internal diameters within the tubing string sections to handle higher volume fluids for stimulation of the earth formations.

When the sealing assemblies are within the sealing bores 22 and 23, then the packer bores are sealed off by the packing elements 29 and 32 and an enclosed volume 40 is formed between the packer bores 22 and 23 of the upper and lower receptacles. The enclosed volume 40, as shown in FIG. 2, is defined by the bore 41 of the casing intermediate of the upper and lower sealing assemblies 26 and 27. The effective cross-sectional area for the lower seal assembly is designated by the symbol A₁. The effective cross-sectional area across the upper assembly is designated by the symbol A₂. The arrows illustrated on the areas indicate the direction of forces when hydraulic pressure is applied to the areas. The upper packer bore 22 is larger in diameter than the lower bore 23 and would ordinarily contain a larger cross-sectional area. However, the seal assembly 26 has an opening 42 extending longitudinally therethrough and the cross-sectional area of the opening is design-

nated as A_3 . The area A_3 is sized so that the effective cross-sectional area across each of the packer bores is substantially equal. Thus, area A_1 is equal to area A_2 minus area A_3 . When hydraulic pressure is applied to the areas A_1 and A_2 , there is no unbalance in the areas to create forces tending to move the seal assemblies relative to the bores 22 and 23. At the upper end of the opening 42 through the packer seal assembly 26 is an enlarged bore 43 (FIG. 1) which has an upwardly facing shoulder and which received the lower end of a tubular stinger 44. The stinger has a circumferential annular sealing device 46 so that when the stinger is disposed within the bore 43, a sealing relationship is made with respect to the seal assembly. The stinger 44 in turn is coupled to a "short" string of tubing 45 and can be inserted and removed by straight up and down motion.

In the foregoing operation, both strings of tubing and the seal assemblies are recovered by straight pick-up on the tubing strings and will leave an unrestricted inside diameter of the casing for remedial type of work. This eliminates unnecessary costs which is involved in drilling out permanent type packers and also possible formation damage. Additionally, there are no mechanical devices such as latches or hold-downs which can stick in the well. To treat the lower zone, weight is applied to the long tubing string so that the seal assemblies are held in place by the weight on the upper seal assembly and to accommodate changes in tubing length due to temperature. Inhibiting fluid is introduced into the upper zone before connecting the short string to the upper seal assembly. The lower zone can be acidized for example with hydrochloric acid, and flushed in a well-known manner. The upper zone, that is, the zone between the upper and lower receptacles then can be treated with hydrochloric acid by pumping such acid down the short string and flushed in a well-known manner. Because the effective areas across the packer seals are substantially equal, there is no net effect upon the seal assemblies tending to move them because the upwardly directed force resulting from the piston action on the upper seal assembly is counteracted by the downwardly directed force on the lower seal assembly.

During an acidizing treatment, occasionally the tubing string will alter its length because of temperature changes and thus the tubing can shorten. The length of the upper packer bore receptacle is long enough to permit the movement of the seals during the treatment.

However, during production of the well, the seals are retained in position so they do not incur wear during operation and consequently the seals last longer.

Summing up the present system, the "long" string preferably includes a section 28 of heavy $2\frac{1}{8}$ in., 8.70 lbs. tubing between the seal assemblies, a section 34 of $2\frac{1}{8}$ in., 6.50 lbs. tubing to a location above the end of the casing 14, and then a string of tubing 36 of $3\frac{1}{2}$ in., 10.30 lbs. tubing to the surface. When the sealing assembly 27 is landed on flange 37, additional weight should be applied to provide compression to the tubing. The short string can include $3\frac{1}{2}$ in. and $2\frac{1}{8}$ in. tubing with a stinger to seal in the bore 43. Both Zones A and B can then be independently and sequentially treated with acid without requiring any further equipment such as hold-downs or removal of the strings from the well bore.

While there have been described what are at present considered to be preferred embodiments of this invention, it will be obvious to those skilled in the art that various changes and modifications may be made therein without departing from the invention, and it is, therefore, intended to cover all such changes and modifications as fall within the true spirit and scope of the invention.

What is claimed is:

1. A method for treating at least two spaced-apart strata in a well bore traversing earth formations where said strata are opened to the interior of a tubular assembly and the assembly has upper and lower packer bores disposed to straddle the upper strata, closing off said upper and lower packer bores with substantially equal, effective cross-sectional upper and lower areas while providing with a first string of tubing a flow conduit through said packer bores where the flow conduit extends from the earth's surface to the lower strata, connecting a second tubing string through the closed upper packer bore to the volume defined between the upper and lower areas, and applying weight on the first string of tubing while introducing a fluid to the upper strata through the second string of tubing.
2. A method for treating at least two spaced-apart strata in a well bore traversing earth formations where said strata are opened to the interior of a tubular assembly and the assembly has upper and lower packer bores disposed to straddle the upper strata, closing off said upper and lower packer bores with substantially equal, effective cross-sectional upper and lower areas while providing with a first string of tubing, a flow conduit through said packer bores where the flow conduit extends from the earth's surface to the lower strata, applying weight on the first string of tubing to accommodate changes in tubing length due to temperature, lowering a second tubing string to the upper packer bore and introducing an inhibiting fluid to volume defined between the upper and lower areas, connecting said second tubing string through the closed upper packer bore to the volume defined between the upper and lower areas, introducing acid through said first string of tubing to said lower strata, flushing said acid from said lower strata, introducing acid through said second string of tubing to said upper strata, and flushing said acid from said upper strata.
3. A method for completing a well traversing earth formations comprising the steps of: locating a tubular packer bore receptacle assembly having upper and lower packer bores in a borehole so that such packer bores straddle an earth strata for production of hydrocarbons, cementing said receptacle assembly in such a location and placing said earth strata into fluid communication with the bore of such packer bore receptacle assembly intermediate of such upper and lower packer bores, closing off the lower and upper packer bores with packing means associated with a string of tubing to form an enclosed volume between said lower and upper packer bores where said enclosed volume is

defined by the bore of packer bore receptacle assembly and the upper and lower cross-sectional areas exclusive of the cross-sectional area of such string of tubing,

introducing a well treating fluid under pressure through said upper packing means to said enclosed volume where said upper and lower cross-sectional areas are adjusted to substantially balance the said upper and lower cross-sectional areas to effectively equal amounts thereby to equalize the upward and downward forces on the string of tubing within said enclosed volume and treating the earth strata intermediate of said upper and lower packer bores.

4. Apparatus for use in oil and gas wells which traverse earth formations comprising:

a packer bore receptacle assembly adapted for cementing in place in a borehole, said receptacle assembly having upper and lower packer bores, packer sealing means including an upper packer sealing assembly and a lower packer sealing assembly, said sealing assemblies being constructed and arranged for a sliding and sealing reception respectively in said upper and lower packer bores, said sealing assemblies being coupled to one another and spaced-apart by a section of tubing so that when said upper packer sealing assembly and said lower packer sealing assembly are slidingly and sealingly received in said upper and lower packer bores that upper and lower cross-sectional areas are defined,

means defining a flow conduit through said upper cross-sectional area, said flow conduit means being sized in cross-sectional area relative to said upper cross-sectional area whereby the effective areas of said upper and lower cross-sectional areas are substantially equal.

5. The apparatus of claim 4 wherein said upper packer bore has a first polished uniform diameter extending between a first, inwardly extending shoulder and a second, outwardly extend-

ing shoulder, where said second shoulder is disposed above said first shoulder,

said lower packer bore has a second polished uniform diameter extending between a third, inwardly extending shoulder and a fourth, outwardly extending shoulder, where said fourth shoulder is disposed above said third shoulder,

said upper and lower packer sealing assemblies respectively having first and second sealing elements thereon, fifth and sixth downwardly facing shoulders, respectively located below each of said sealing elements, said section of tubing spacing, said fifth and sixth shoulders from one another so that upon engagement of the fifth shoulder with the third, inwardly extending shoulder, that the sixth shoulder is located above the first, inwardly extending shoulder.

6. The apparatus of claim 5 wherein said first and second sealing elements are slightly compressible and slightly greater in diameter than the diameters of the respective packer bores.

7. The apparatus of claim 4 wherein said flow conduit means includes an upper polished bore with an inwardly extending shoulder and a tubular member constructed and arranged for sliding and sealing reception into said upper polished bore and engagement with said inwardly extending shoulder.

8. The apparatus of claim 4 wherein said packer bore receptacle assembly includes means for anchoring said assembly within another tubular well member.

9. The apparatus of claim 4 wherein the effective area of said upper cross-sectional area is defined by the diameter of said upper packer bore less the cross-sectional area for said flow conduit and the cross-sectional area for said section of tubing and the effective area of said lower cross-sectional area is defined by the diameter of said lower packer bore less the cross-sectional area for said section of tubing.
